MATTRESS CONSTRUCTION
Robert T. Clifton, 4828 Kathleen Ave.,
Castro Valley, Calif.
Filed Oct. 31, 1960, Ser. No. 66,024
2 Claims. (Cl. 5—351)

This invention generally relates to the art of constructing mattresses, and is particularly directed to an improved mattress construction whereby proper support is given to previously neglected portions.

A variety of mattress constructions are well known in the art which are intended to adjust to the complex loading presented by the varied weight of the human body and provide a firm relaxing support to every part thereof. By virtue of the major portion of body weight being concentrated in the region of the hips, it has been suggested for example, to increase the strength of the mattress on such region. However, irrespective of the hardness or softness of conventional mattresses, no presently available mattress takes into account the provision of support for the small or bridge of the back of the person using the mattress. It is quite apparent that the small of the back is a critical region, and lack of adequate support therefor during the hours of sleep will frequently result in back aches, in much the same manner as the lack of an arch in a shoe during walking for extended periods of time would deleteriously affect the wearer's foot.

It is therefore an object of the present invention to provide an improved mattress having enhanced support in the area of the small of the back of the user.

Another object of the invention is the provision of a mattress of the class described having improved back supporting characteristics and a materially extended life.

Still another object of the invention is to provide a mattress of double bed size which has strengthened back supporting sections on opposite sides of its center individually positioned to conform to the bodies of the particular individuals who are to normally occupy the respective sides thereof.

It is a further object of the invention to provide a mattress of the class described which provides improved back support irrespective of the side of the mattress that is exposed.

The invention possesses other objects and features of advantage, some of which, with the foregoing, will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

FIGURE 1 is a plan view of a preferred embodiment of the mattress of the present invention with portions broken away to show its structure;

FIGURE 2 is a sectional view on an enlarged scale taken at line 2—2 of FIGURE 1; and

FIGURE 3 is a view similar to FIGURE 2 but illustrating a modified form of the structure.

Referring now to the drawing, there is shown a mattress 11 constructed in accordance with the invention and which as illustrated and described in the ensuing description is of double-bed size and inner spring design, although the principles of the invention are equally applicable to mattresses of all sizes and different designs. The mattress 11 is of generally conventional construction and includes a plurality of coil springs 12 arranged in a series of rows to define a regular geometric matrix configuration in plan. The springs of transversely adjacent rows on one side of the longitudinal center line of the matrix configuration are secured together at their tops

2

and bottoms by a plurality of longitudinally spaced resilient transverse tie members 13. The springs 12 on the opposite side of the center line are similarly secured together by a plurality of resilient transverse tie members

5 14. In addition, the springs in the groups thereof disposed on opposite sides of the matrix center line are respectively marginally secured at their tops and bottoms by resilient frame members 16, 17 and the transverse tie members 13, 14 are respectively secured thereto. In the resulting overall mattress core structure 18, the longitudinally adjacent halves 19, 21 thereof are hence substantially independent so as to separately support a pair of individuals reclining on opposite sides of the inner spring. The individual springs 12 of each half are, moreover, substantially independently compressible to provide uniform overall body support in the usual manner. It will be understood, however, that the principles of this invention, presently to be described, are equally applicable to twin or single size mattress.

The mattress core structure 18 is covered at its top and bottom faces by insulation layers 23, 24 of hard fiber cordage, such as sisal, which prevent "coil spring feel" as is conventional in the art. Cushioning such as dual layers 26, 27 and 28, 29 of felt or the like is in turn disposed in overlying relation to the insulation layers 23, 24 to provide cushioned surfaces at the top and bottom surfaces of the mattress. Padded side panelling 31 is then secured about the side surfaces of the core and the entire structure is covered and tied together by means of ticking 32.

It will be appreciated that the mattress construction so far described is substantially conventional. As pointed out hereinbefore such a mattress provides no substantial support for the small of the back of the user, the user's torso weight being distributed to the hip area and the upper back area, resulting in discomfort to the user and likewise resulting in eventual sagging of the mattress in the areas of greatest weight support. With the foregoing in mind, I have minimized the sagging tendency in the hip and upper back supporting regions and materially lengthened mattress life and more importantly by the provision of strengthened supporting sections in the regions of the small of the back of the user. More particularly, in the instance of a double bed mattress, as shown

45 in FIGURES 1 and 2, the strengthened sections may be provided by linear "no sag" springs 33, 34 respectively secured transversely between the side portions of the upper frame members 16, 17 and secured to the springs of a pair of transversely adjacent rows thereof in similar fashion as the tie members 13, 14. It is particularly important to note that the no sag springs 33, 34 are individually longitudinally positioned to correspond to the respective positions of the small of the back of the two individuals who will normally occupy the opposite sides of the mattress. As illustrated, the spring 33 is spaced closer to the head end of the mattress than is the spring 34. Thus in the illustrative example, the strengthening or supporting springs are positioned to accommodate a relatively short person, e.g., a woman, on the half 19 of the mattress core and a taller person, e.g., a man, on the half 21 thereof. Mattresses of double bed size in accordance with the present invention may hence be provided with the strengthening springs 33, 34 at a wide variety of combinations of individual longitudinal positions to conform to the requirements of substantially all couples in accordance with their individual heights.

Provision is also made in the mattress of the present invention such that it may be turned over or inverted and still present individually positioned small of the back supporting sections at the upper surface thereof. To this end, a second set of no sag springs 33', 34' are respec-

tively secured between the side portions of the lower frame members 16, 17 at comparable positions as springs 33, 34 but with the mattress inverted from head to foot. In other words springs 33', 34' are spaced from the foot by the same distances the springs 33, 34 are spaced from the head of the mattress.

It will be appreciated that various alternatives to the no sag springs 33, 34 may be employed to provide the strengthened small of the back supporting sections in the mattress construction. For example, as depicted in FIGURE 3, rubber pads 36, 37 and 36', 37' may be alternatively employed in place of the no sag springs.

It will be understood that notwithstanding the addition of the added supporting means for the small of the back, the appearance of the mattress will not be modified, and in merely feeling the mattress, it is questionable whether its presence can be detected. It will further be understood that the height of the bridge of the user's back varies, as does the weight and accordingly the strength or resistance offered by such means may be properly correlated thereto. In other words, the supporting means is intended to supply a support for the small of the back, but not apply pressure thereto.

What is claimed is:

1. A double-bed mattress comprising a core of a plurality of coil springs arranged in a matrix configuration with the springs of adjacent transverse rows on opposite sides of the longitudinal center line of the matrix being respectively secured at their tops and bottoms to resilient transverse tie members secured between the side portions of resilient top and bottom frame members respectively encompassing the groups of springs on opposite sides of said center line and secured thereto, a resilient elongated support member secured transversely between the side portions of one of the top frame members and secured to the springs of a pair of transversely adjacent rows thereof at a longitudinal position adapted to be in supporting relation to the small of the back of a first occupant, a second resilient elongated support member se-

cured transversely between the side portions of the second of said top frame members and secured to the springs of a pair of transversely adjacent rows thereof at a longitudinal position adapted to be in supporting relation to the small of the back of a second occupant, a third resilient elongated support member secured between the side portions of the bottom frame member opposed to said first upper frame member and secured to the springs of a pair of transversely adjacent rows thereof at a longitudinal position spaced from one end of the core by an equal amount as said first support member is spaced from the opposite end of the core, a fourth resilient elongated support member secured between the side portions of the bottom frame member opposed to said second upper frame member and secured to the springs of a pair of transversely adjacent rows thereof at a longitudinal position spaced from one end of the core by an equal amount as said second support member is spaced from the opposite end of said core, and a covering encompassing said core.

2. In a double bed mattress including a core with independent coil spring sections on opposite sides of the longitudinal center line thereof, the combination comprising a pair of elongated substantially planar resilient strengthening members extending transversely of the mattress adjacent the upper portion of said sections and respectively secured thereto at longitudinal positions which during occupancy by a couple respectively underlies the small of their backs.
